UNITED STATES PATENT OFFICE.

FRANK H. ANTHOS, OF BOSTON, MASSACHUSETTS, ASSIGNOR OF ONE-EIGHTH TO DEMETRIUS GEORGE CARZIS, OF CAMBRIDGE, MASSACHUSETTS, ONE-EIGHTH TO JAMES CARZIS, ONE-EIGHTH TO JOHN G. CARZIS, AND ONE-EIGHTH TO GEORGE PICRADIS, ALL OF LYNN, MASSACHUSETTS.

METAL HEEL.

1,417,881.

Specification of Letters Patent. Patented May 30, 1922.

Application filed July 30, 1920. Serial No. 400,168.

To all whom it may concern:

Be it known that I, FRANK H. ANTHOS, a subject of the King of Greece, residing at Boston, county of Suffolk, State of Massachusetts, have invented an Improvement in Metal Heels, of which the following description, in connection with the accompanying drawing, is a specification, like characters on the drawing representing like parts.

10 This invention relates to metal heels, such as are used on ladies' shoes, and it has for its object to provide a novel heel and a novel means of attaching the heel to the shoe.

The invention comprises a heel body and 15 an attaching plate which is adapted to be nailed to the heel seat of the shoe, and to which the heel body may be detachably secured.

In order to give an understanding of my 20 invention, I have illustrated in the drawings a selected embodiment thereof, which will now be described, after which the novel features will be pointed out in the appended claim.

25 In the drawings, Fig. 1 is a side view of a portion of a shoe having my improved heel attached thereto.

Fig. 2 is a plan view of the attaching plate.

Fig. 3 is a top plan view of the heel body.

30 Fig. 4 is a bottom plan view of the heel body.

Fig. 5 is a sectional view through the heel.

1 indicates a portion of a shoe having the 35 usual heel seat portion 2 to which the heel is attached.

My improved heel comprises a body portion 3 which is made of metal, and an attaching plate 4 which is secured to the heel 40 seat 2 and to which the heel body 3 is attached.

This attaching plate 4 is skeleton shaped, it having the portion 5 which fits around the periphery of the heel seat, and which is provided with a plurality of nail holes 6 to receive nails 7, by which said plate may be nailed to the heel seat of the shoe as shown in Fig. 5. This attaching plate is also provided with arms 8 which extend from the 50 portion 5 to a central hub portion 9, and which are bent downwardly so that the hub

portion 9 stands considerably below the plane of the main portion 5.

The heel body 3 is in the form of a shell and the arms 8 are so shaped that when 55 the attaching plate 4 rests on top of the heel body, the arms will meet the walls of the heel body and fit the contour thereof. The heel body is provided with positioning ribs 10 on its inner face, which ribs are situated 60 so that they engage the sides of the arms 8. These ribs, therefore, by their engagement with the arms 8 serve to maintain the attaching plate in proper position relative to the heel body. 65

The heel body is provided near its lower end with a partition 11 having an aperture 12 therein adapted to receive an attaching screw 13, which is screw-threaded into the hub 9. This screw serves to clamp the heel 70 body and attaching plate firmly together.

The bottom of the heel may be provided with a top lift of rubber, leather, or any other suitable material. Such top lift is shown at 14 and it is secured to the heel body 75 by three screws 15, that are screw-threaded into screw-threaded apertures 16 formed in the bottom of the heel. The partition 11 is situated a slight distance above the bottom of the metal heel body, thus leaving a pocket 80 17, and I propose to place a spacing member 18 of leather, rubber or suitable material in said pocket to properly support the top lift 14.

In attaching my improved heel to the shoe, 85 the first operation is to nail the attaching plate 4 to the heel seat by the nails 7. After this is done, the heel body is placed in position with the ribs 10 embracing the arms 8, and the screw 13 is inserted through the 90 aperture 12 and screwed into the hub 9. The tightening of the screw will clamp the heel body firmly to the attaching plate, and the cooperation of the ribs 10 with the arms 8 serve to securely hold the heel body in position and prevent it from turning. 95

After the heel body has been secured to the attaching plate, the filling member 18 is inserted in the recess 17 and the top lift 14 is then screwed to the heel body by 100 the screws 15. This completes the operation and the shoe is then ready for use.

My improved heel is especially advantageous for cobblers and other people who repair shoes, because it can be attached by any one after the shoe is made, and without in any way injuring the shoe.

While I have illustrated herein a selected embodiment of my invention, I do not wish to be limited to the constructional features shown.

10 I claim:

In a heel, the combination with a hollow heel body having a flaring upper end, of a skeleton attaching plate having a peripheral portion adapted to rest against and be secured to the heel seat of a shoe, a central

hub portion situated below the peripheral portion and located within the hollow heel body, and curved arms connecting the hub portion and peripheral portion, said arms lying against and having a shape to fit the 20 contour of the inner wall of the flaring end of the heel body, said body having ribs on its inner face which engage the side edges of the arms and retain the heel body and attaching plate in proper relative position, and 25 a screw extending through the heel body and screw-threaded into the hub.

In testimony whereof, I have signed my name to this specification.

FRANK H. ANTHOS.
